UNITED STATES PATENT OFFICE.

GEORGE WHITCOMB, OF SPRINGFIELD, OHIO.

IMPROVEMENT IN MOLE-PLOWS.

Specification forming part of Letters Patent No. 25,988, dated November 1, 1859.

To all whom it may concern:

Be it known that I, GEORGE WHITCOMB, of Springfield, in the county of Clarke and State of Ohio, have invented a new and useful Improvement in Mole-Plows, of which the following is full and exact description, reference being had to the accompanying drawings, and to the letters marked thereon.

Figure 1 is a perspective view showing the mold complete, and Fig. 2 a section showing the mold cut longitudinally through the center and exhibiting the construction and arrangement of the same.

A is a draft-beam which holds the cutter B, to which the front of the mold C is attached.

D, E, F, G, H, and I are concave rings strung upon the chain J and held by the nut U, having bearings R R R R R R. The rings D, E, F, G, H, and I fit into each other in such a manner as to resemble the body of a serpent. When the mold is bent the rings or sections pass over each other, similar to the rings or

scales upon the serpent. The advantage thus to be derived is obvious from the fact that the mode of its construction gives it a free elastic serpentine movement in every way, giving it the capability of going around stumps, stones, hillocks, or any other obstruction without injuring the face of the ditch, the cavity being left perfectly smooth, for by the flexibility gained by this improvement in mole-plows a perfect ditch can be made circuitously in the diameter of eight feet.

What I claim, and desire to secure by Letters Patent, is—

The construction of a flexible mold by the combination of sections which are not attached to each other, but by being held in place by the chain J or its equivalent, as set forth.

GEORGE WHITCOMB. [L. S.]
